UNITED STATES PATENT OFFICE.

JOHN W. LENLING, OF GROTON, SOUTH DAKOTA.

ANCHORING MEANS FOR WIRE TENSIONERS.

Original application filed August 1, 1924, Serial No. 729,657. Divided and this application filed February 21, 1925. Serial No. 10,921.

To all whom it may concern:

Be it known that I, JOHN W. LENLING, a citizen of the United States, residing at Groton, in the county of Brown and State 5 of South Dakota, have invented certain new and useful Improvements in Anchoring Means for Wire Tensioners; and I do declare the following to be a full, clear, and exact description of the invention, such as 10 will enable others skilled in the art to which it appertains to make and use the same.

This application forms a division of my pending U. S. application, Serial No. 15 729,657, filed August 1st, 1924. This pending application is now devoted, due to the requirement for division, to the protection of a wire tensioning device, whereas this 20 divisional application is directed to novel means for connecting the wire tensioning device with an anchoring stake or the like, it being understood that the present invention might also be used for connecting practically any kind of a body with an anchoring 25 stake or the equivalent of the latter.

The object of the invention is to provide an extremely simple and inexpensive construction for connecting the body with a stake and providing means also to be 30 engaged by the operator's foot, so that he may readily force the stake into the ground.

With the foregoing in view, the invention resides in the novel subject matter hereinafter described and claimed, the description being supplemented by the accompanying drawing.

Figure 1 is a side elevation showing the anchoring means attached to a tensioning device of the type disclosed in the above- 40 identified pending application.

Figure 2 is a top plan view of the parts shown in Fig. 1.

Figure 3 is a perspective view of the anchoring means.

In the drawing above briefly described, B designates an elongated body to be anchored, said body in the present disclosure, constituting part of a wire-tensioning device and having a suitable connection C 45 at one end for engagement with the wire. For anchoring the other end of the body B to a stake S or to some equivalent member, I provide a novel construction and arrangement of parts. A pair of elongated metal plates 1 are secured by bolts or the

like 2 to opposite sides of the body B adjacent the last named end of said body, said plates being bent laterally inward at 3 around this end of the body and being then extended from the latter to form a 60 pair of parallel arms 4. These arms have outwardly bowed portions 5 between their ends to embrace the stake S and have their terminals 6 extended beyond said portions 5 to be engaged by the user's foot, so that 65 downward pressure may be exerted to force the stake S into the ground. The arms are of course clamped to the stake and this may well be accomplished by passing a pair of bolts 7 through said arms at opposite sides 70 of their bowed portions 5.

By providing the construction shown and described, it will be seen that simple and inexpensive, yet efficient and desirable means have been provided for anchoring any desired body to a stake or the like, said means being adapted to be engaged by the user's foot, so that said stake or other member 75 may be forced into the ground.

As excellent results are obtainable from 80 the details disclosed, they are preferably followed, but within the scope of the invention as claimed, modifications may of course be made.

I claim:

1. In an anchor for a body, a pair of elongated metal plates having laterally spaced end portions adapted to be secured to opposite sides of the body near one end thereof, said plates being bent laterally inward on lines transverse to their width to about said end of the body and being then directed laterally in a direction parallel to said laterally spaced end portions to provide a pair of stake-clamping arms, said arms having transversely disposed outwardly bowed stake-embracing portions between their ends, the free terminals of said arms projecting beyond said stake-embracing portion and being adapted to be engaged by 90 the user's foot to permit him to force the stake into the ground, and means for clamping the outwardly bowed portions of said arms against opposite sides of the stake. 95

2. In an anchor for a body, a pair of elongated metal plates having flat laterally spaced parallel end portions adapted to be secured to opposite sides of the body near one end thereof, said plates being bent laterally inward at right angles on transverse 100 105 110

lines to abut said end of the body and then directed laterally at right angles in a direction parallel to said parallel end portions to provide a pair of stake-clamping arms, 5 said arms having outwardly bowed stake-embracing portions between their ends, the free terminals of said arms projecting beyond said stake-embracing portions and being adapted to be engaged by the user's

foot to permit him to force the stake into the ground, and clamping bolts passing through said arms at opposite sides of said stake-embracing portions to clamp said portions against the stake.

In testimony whereof I have hereunto 15 affixed my signature.

JOHN W. LENLING.
